(57) **CLAIM**

I claim the ornamental design for a reflective stripe, as shown and described.

DESCRIPTION

FIG. 1 is a front elevation view of an embodiment of a reflective stripe showing the new design;

FIG. 2 is an exploded perspective view thereof;

FIG. 3 is a perspective view thereof;

FIG. 4 is a cross-sectional view thereof, taken along line 4-4 in FIG. 3; and

FIG. 5 is a detail view showing reflective surfaces visible through non-reflective mesh.

FIG. 6 is a front elevation view of another embodiment of a reflective stripe showing the new design;

FIG. 7 is an exploded perspective view thereof;

FIG. 8 is a perspective view thereof;

FIG. 9 is a cross-sectional view thereof, taken along line 9-9 in FIG. 8; and,

FIG. 10 is a detail view showing reflective surfaces visible through non-reflective mesh.

Broken lines and the area within the broken lines represent environmental subject matter that forms no part of the claimed design.

The shading lines oblique to the normal orientation of the drawing sheets illustrate surfaces that are reflective.
